UNITED STATES PATENT OFFICE.

LOUIE A. SHERMAN, OF KANSAS CITY, MISSOURI, ASSIGNOR TO ROTARY VALVE MANUFACTURING COMPANY, OF KANSAS CITY, MISSOURI, A CORPORATION OF MISSOURI.

VALVE.

1,143,865.

Specification of Letters Patent. Patented June 22, 1915.

Application filed September 14, 1914. Serial No. 861,510.

To all whom it may concern:

Be it known that I, LOUIE A. SHERMAN, a citizen of the United States, residing at Kansas City, in the county of Jackson and State of Missouri, have invented certain new and useful Improvements in Valves; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a rotary valve for explosive engines, and has for its principal object, to provide a device of this character, wherein the intake and exhaust members are balanced relative to the explosion chamber, to obviate thrust and friction of the valve members in their casing.

It is also an object of the invention to provide a rotary valve wherein the intake of clean gas passes over the spark plug to 25 scour the plug while the valve is in operation.

It is also an object of the invention to provide a rotary valve wherein all of the valve members for a plurality of cylinders may 30 be mounted on a common shaft to insure proper timing.

In accomplishing these and other objects of the invention, I have provided the improved details of structure hereinafter described and illustrated in the accompanying drawings, wherein:—

Figure I is a perspective view of an explosive engine equipped with a rotary valve constructed in accordance with my invention. Fig. II is an enlarged longitudinal section of an engine cylinder and valve casting on the line II—II, Fig. III, showing the spark plug and its relation to the valve and cylinder. Fig. III is a cross section on the line III—III, Fig. II, showing the valve in longitudinal section and illustrating its relation to the intake, exhaust and cylinder ports. Fig. IV is an end view of the cylinder head, showing the relative positions 50 of the valve ports. Fig. V is an enlarged

detail perspective of the valve sleeve, showing the spark plug, and the exhaust and cylinder ports. Fig. VI is a detail perspective view of the valve, showing the spaced valve members with their ports.

55

Referring more in detail to the parts, 1 designates an explosive engine of any ordinary type, and comprising a single cylinder 2, a connecting rod 3, crank shaft 4 and fly-wheels 5; the said cylinder comprising 60 a casing having an ordinary water jacket 7, and having its open outer end closed by a head 8, having a water jacket 9 communicating with the casing jacket 7.

The combined water jacket 7—9 is fed 65 through circulating pipes 10 and 11 in the ordinary manner and for the usual purpose, and the cylinder 2 is provided with the ordinary reciprocatory piston 12.

On the outer face of the cylinder head 8, 70 is a transverse boss 14, having a longitudinal channel 15 provided with a port 16 that opens into the cylinder chamber 17 and opposite the cylinder port 16, with an aperture 19 for containing an ordinary spark plug 75 20; the arrangement described locating the spark plug outwardly from the center of the cylinder and feed port 16.

Fixed in the head boss channel 15 is a sleeve 21, having its ends closed by cap members 22 that are provided with central bearings 23 for carrying a rotary valve shaft 24, which will presently be described; the body of the sleeve being provided with a port 25 that registers with the cylinder port 16 and exhaust port 26 that opens into an exhaust pipe 27 that leads from the cylinder, and an intake port 28 (Fig. III) that opens into a feed conduit 29 through which fuel gas is delivered to the valve from a carburetor 30 (Fig. I).

Fixed on the shaft 24 within the sleeve 21, preferably by welding, or in any suitable manner, are spaced valve-bells 32—32', each of which has a closed outer end 33 and 95 open inner end 34; the open ends of the bells being spaced to form an annular port that constantly registers with the port 25 in the fixed sleeve 21, and with the cylinder port 16; the shaft 24 having bosses 35 there-

100

on for engaging the closed ends of the valve-bells to positively space same and maintain the delivery width.

The valve-bell 32 is provided with a port 37 that is adapted to register with the intake port 28 in the fixed sleeve 21 and the other valve-bell 32' has a similar port 38 that is adapted for registration with the exhaust port 26 in said sleeve, so that as the valve is 10 revolved within the sleeve, it alternately registers with the intake and exhaust ports, but is in constant communication with the engine cylinder.

Each of the valve-bells 32-32' is provided with a gasket or packing ring 39 at each side of its port, and preferably set into a groove in the bell, in order that the bell may fit with sufficient looseness to provide free rotation in its sleeve, but at the same 20 time prevent leakage of gas to or from the cylinder.

The spark plug 20 that is fixed in the aperture 19 in the outer face of the head boss 8, is of any ordinary construction, and its 25 inner end is threaded into an aperture 41 in the sleeve 21 to hold the valve and sleeve in place and properly center the plug over the cylinder port.

While I have shown the engine as of a 30 one cylinder type, it is apparent that any number of cylinders may be used, and that when the cylinders are arranged in parallel relation, the valves for all of the cylinders may be mounted on the same shaft, in order 35 to secure proper timing in all of the cylinders.

As a means for rotating the shaft and valves, I show the shaft 24 provided with a worm gear 43, which meshes with a mating 40 gear 44 on a shaft 45 that is driven by a suitable gearing 46 from the crank shaft 4, although I do not wish to limit myself to any particular mechanism for rotating the valve.

45 In using the valve, presuming the parts to be constructed and assembled as described, when the engine is in operation, gas is taken from the carburetor to the valve-bell 32, so that when the valve port opens to the intake, 50 the gas passes into and through the valve and over the spark plug into the cylinder. Compression takes place as usual, and when the charge is exploded, the engine is cleaned in the usual manner; the parts being so combined and arranged that the cleaning stroke 55 of the engine occurs as the port in the exhaust valve-bell 32' comes into registration with the exhaust pipe.

It is apparent that with this construction the valve is always open to the cylinder, and that the compression and expansion following an explosion is communicated to the valve-bells and valve sleeve, so that thrust and friction must necessarily occur.

By arranging the valve as described, the 65 thrust and friction is balanced, so that there is no twisting strain on the valves or their carrying shaft.

Having thus described my invention, what I claim as new therein, and desire to secure 70 by Letters-Patent, is:

1. The combination with an engine cylinder, of a valve chamber having a cylindrical channel, a sleeve fixed in said channel and provided with intake and exhaust ports, 75 and having an intermediate cylinder port, intake and exhaust conduits in constant communication with the sleeve intake and exhaust ports, a shaft revolvably mounted in the sleeve, and paired valves fixed on the 80 shaft and spaced on opposite sides of the cylinder intake port, and having intake and exhaust ports adapted for intermittent registration with the sleeve intake and exhaust ports. 85

2. The combination with an engine cylinder, of a valve chamber having a cylindrical channel, a sleeve fixed in said channel and provided with intake and exhaust ports, and having an intermediate cylinder port, intake 90 and exhaust conduits in constant communication with the sleeve intake and exhaust ports, a shaft revolvably mounted in the sleeve, paired valves fixed on the shaft and spaced on opposite sides of the cylinder intake port, and having intake and exhaust 95 ports adapted for intermittent registration with the sleeve intake and exhaust ports, and a spark plug projected through the sleeve and between the valves. 100

3. A rotary valve comprising a sleeve having a laterally opening slot, an aperture opposite said slot adapted to receive a spark-plug, and a port adjacent each side of said slot, and a pair of facing valve members adjacent opposite sides of the slot and spark-plug, and having apertures adapted for successive registration with said ports. 105

4. A rotary valve comprising a sleeve having a plurality of apertures, a bearing plate 110 in each end of said sleeve, a shaft revolvably mounted in said bearing plates, a pair of facing valve members rigidly mounted on said shaft having apertures adapted for successive registration with said sleeve ports. 115

5. A rotary valve comprising a sleeve having a laterally opening slot, an aperture opposite said slot for receiving a spark-plug, and a port adjacent each side of said slot, a bearing plate in each end of said sleeve, a 120 shaft revolvably mounted in said bearing plates, and a pair of inwardly facing valve members rigidly mounted on said shaft adjacent the sides of said slot and on opposite sides of said spark-plug, and having apertures adapted for successive registration with said sleeve ports. 125

6. The combination with an engine cylin-

der having intake and exhaust ports, of a sleeve having a slot communicating with the interior of said cylinder, and a port on each side of said slot communicating respectively with the intake and exhaust ports of the cylinder, a bearing plate in each end of said sleeve, a shaft revolvably mounted in said head, a pair of inwardly facing valve members on said shaft, having apertures adapted

for successive registration with said sleeve 10 ports, and means for actuating said valve members.

In testimony whereof I affix my signature in presence of two witnesses.

LOUIE A. SHERMAN.
